UNITED STATES PATENT OFFICE.

BENJN. W. HENDRICK AND H. HENDRICK, OF PROVIDENCE, RHODE ISLAND.

WEAVING-LOOM.

Specification of Letters Patent No. 2,616, dated May 12, 1842.

To all whom it may concern:

Be it known that we, BENJAMIN W. HENDRICK and HORACE HENDRICK, of the city of Providence, in the county of Providence and

5 State of Rhode Island, have invented certain Improvements in Power Looms, by means of which the let-off and take-up motions are governed in a manner more advantageous than has heretofore been done, and by 10 which also the cloth-beam is made to yield to the varying tension of the threads constituting the warp, which varying tension results from the working of the harness; and we do hereby declare that the following is 15 a full and exact description thereof.

In the accompanying drawings we have represented the manner in which we arrange our apparatus, under two different modifications thereof, the two, however, being substantially the same in their general arrangement and action and the change in their form being such only as is necessary to adapt the improvement to the difference in the framework of looms already made.

25 Figure 1, is one end of a loom, as it would be seen in a vertical section from front to back, made at the distance of a few inches from the end frame, and looking at it from the interior. A, A, is the end frame; B, the yarn beam, and C, the cloth beam. D, is a shaft leading from the yarn beam to the cloth beam, and having a worm wheel, or endless screw, at each end of it. The endless screw E, gears into the toothed wheel F, on 30 the end of the yarn beam, on its underside, and the endless screw, or worm wheel, G, at the opposite end gears into the upper side of the toothed wheel H, on the cloth beam. The worm, or screw, E, is firmly attached 35 to the shaft D, but the worm wheel G, is tubular, so that it can turn, or play, back and forth, upon the shaft D. It has attached to it a clutch, or coupling, wheel I, the teeth of which fit into those of a corresponding clutch wheel J, made fast to the 40 shaft D. Upon this shaft there is a spiral spring K, by which the clutch wheels are kept in contact with each other when not subjected to a force which would overcome 45 this tension of the spring.

The screw E, is single threaded and the screw G double threaded; and supposing the wheel F, to be double the diameter of the wheel H, the latter would make four revolutions while the former made one, when the shaft D, was made to revolve; they may, of

course, be so varied in diameter as to cause their motions to correspond with the relative diameters of the yarn and cloth beams, whatever these may be.

50 In the working of the harness up and down, the tension given to the threads constituting the warp is constantly varying, and under the ordinary modes of constructing looms this is productive of much inconvenience and injury, which are completely obviated by the novel mode of arranging the parts as above described. As the warp is strained by the motion of the harness up and down, the cloth beam yields to the force 55 thereby exerted upon it; the teeth of the wheel H, acting upon the worm wheel G, forces it against the spring K, which, yielding, allows the cloth beam to revolve to the required distance, while it is caused to return when the tension is taken off. The teeth of the clutch wheels thus slide upon each other as the harness plays up and down, and when the tension becomes sufficient to force the worm G, back to a sufficient distance, the clutch wheel I, will escape 60 a single tooth, and thus keep the action 70 equal.

The worm wheels, or endless screws, E, and G, are one right, and the other left, 65 handed, and this constitutes an important item in our improvements, as by this device the yarn and cloth beams are made to counteract the tendency of each other to turn, from the tension of the warp, and we are 75 in consequence thereof enabled to dispense with the vertical shaft ratchet wheel, and friction strap, ordinarily used to regulate the connection between the two beams; an arrangement which is not only more complex, but is also less efficient than that 80 adopted by us.

The arrangement for giving to the cloth beam its take up motion differs, in some particulars, from that in ordinary use. The 85 back lever L, on the lathe, is the same with that on other looms, but it is made to act directly on the shaft D, through the intermediate of the ratchet wheel M, and the pawl, or feed hand, N. The back lever L, gives 90 motion to the kneed lever O, having the pawl N, at its upper end, and this carries the shaft D, to the required distance at every 95 beat of the lathe.

Fig. 2, shows the manner in which we, 100 sometimes, adapt our apparatus to the framework of the loom, and is a sectional view,

taken in the same manner with Fig. 1. In this figure, the parts which correspond with those in Fig. 1, are designated by the same letters of reference. The shaft D, is made 5 to operate upon a vertical shaft D', by means of the bevel gear, a, a'; upon this vertical shaft is placed the worm wheel G, and the clutch wheels, and the spiral spring, all constructed and operating as above described. 10 The ratchet wheel M, is placed upon the lower end of the shaft D', and the lever O, is so formed as to act upon the pawl N, in its proper position.

Having thus fully described the nature of our improvements, and shown the manner in which we carry the same into operation, what we claim therein as new, and desire to secure by Letters Patent, is—

1. The manner in which we have com-

bined the two worm wheels with the yarn 20 and the cloth beams; one of said wheels having a right-handed, and the other a left-handed thread, so as to cause them, by their counteraction, to preserve the two beams in their required relative positions, without the 25 aid of a friction band, or of any analogous device.

2. We claim, likewise, the manner in which we have arranged and combined the worm wheel G, the shaft D, the spiral spring 30 L, the clutch wheels I, and J, and the cloth beam, so as to admit of the yielding of the latter with the varying tension of the warp.

BENJAMIN W. HENDRICK.

HORACE HENDRICK.
